UNITED STATES PATENT OFFICE.

JOSEPH KUKLA, OF BUFFALO, NEW YORK, ASSIGNOR OF ONE-HALF TO JOHN GONDEK,
OF BUFFALO, NEW YORK.

RAIL JOINT AND CHAIR.

1,114,369.

Specification of Letters Patent.

Patented Oct. 20, 1914.

Application filed July 3, 1914. Serial No. 848,789.

To all whom it may concern:

Be it known that I, JOSEPH KUKLA, a subject of the Emperor of Austria-Hungary, residing at Buffalo, in the county of Erie 5 and State of New York, have invented certain new and useful Improvements in Rail Joints and Chairs, of which the following is a specification.

This invention relates to new and useful 10 improvements in rail joint and chair.

The primary object of this invention is to provide a means whereby the adjacent ends of railway rails forming the track may be retained in their operative connected positions but at the same time are capable of 15 longitudinal sliding movement for accommodating any contracting or expanding of the rails.

A further object is to provide a rail chair 20 adapted to be firmly secured to the ties and accommodating the adjacent ends of rail way rails slidably therein.

A still further object is to provide a rail chair that may be slidably positioned upon 25 one rail and then moved to a position for connecting one end of said rail to the end of an adjacently positioned rail also adapted to slidably receive the chair thereon.

With these general objects in view and 30 others that will appear as the nature of the invention is better understood, the same consists in the novel combination and arrangement of parts hereinafter fully described, illustrated in the accompanying 35 drawings and pointed out in the appended claims.

In the drawings forming a part of this application and in which like designating characters refer to corresponding parts 40 throughout the several views:—Figure 1 is a side elevation of the device assembled and with one side of the chair broken away. Fig. 2 is a top plan view thereof with the chair and connecting end portions shown in 45 horizontal section. Fig. 3 is a perspective view of one rail end, and Fig. 4 is a vertical transverse sectional view through one of the rails at a point adjacent the chair within which the rail is positioned.

50 Referring more in detail to the drawing, rails 10 and 11 are illustrated secured together by means of a rail chair 12, which chair is adapted to be rigidly secured to the railway ties by means of hold-fast devices 55 such as spikes driven through perforations

13 in the side lugs 14 laterally extending from the chair. The web 15 of the rails is provided with oppositely positioned longitudinal ribs 16, which ribs may be provided for the entire lengths of the rails or only 60 for a desired length at each end of the rails. These ribs 16 have their upper faces cut away and forming upper inclined faces 17 upon said ribs, which faces 17 form V-shaped grooves with the adjacent sides of the rail 65 web 15.

The rail connecting chair 12 is formed with side flanges 18 separated and of an interior configuration complementary to that of the rail end whereby as best illustrated in 70 Fig. 4, the chair may be slidably positioned upon the end of the rail. The inner faces of the chair flanges 18 are provided with longitudinal grooves 19 adapted for the reception of the web ribs 16 while the base 75 flange 20 of the rail is seated upon the base 21 of the chair.

From this construction it will be readily apparent that a rail chair may be slidably positioned at any desired point upon a rail 80 which is constructed of the form illustrated in Fig. 3 and that another rail of similar form may be positioned in accurate alignment therewith and whereupon the chair may be slidably moved to span the adjacent 85 ends of the rails as shown in Figs. 1 and 2. The rigid securing of the chair to the ties permanently retains the rails in their operative positions, but at the same time allows for expansion and contraction. 90

In practice, the grooves 19 will be of a size which will permit ready entry of the web ribs 16 into said grooves 19. To effect therefore, a perfect alining of the rails at their meeting ends, I provide an alining-bar 95 or strip 24 which is seated in a groove 23 provided therefor in the outer face of one of the ribs 16 of one rail, and is received in a similar groove in the corresponding rib of the meeting rail. This bar or strip is preferably secured to one of the rails as by a screw 25 or in any other desired manner. This strip or bar has a neat fit with both rails, alining them perfectly at the joint and in addition serves as a bond between the 100 rails when the latter are separated slightly at the joint.

While the form of the invention herein shown and described is what is believed to be a preferable embodiment thereof, it is 110

nevertheless to be understood that minor changes may be made in the form, proportion and details of construction without departing from the spirit and scope of the 5 invention as claimed.

What is claimed as new is:—

1. A device of the class described comprising rails having opposite longitudinal side ribs integral with the webs thereof, a 10 rail chair provided with side flanges having inner faces formed complementary to the sides of the rail web, the upper faces of said ribs being inclined and forming V-shaped 15 grooves with the adjacent sides of the rail web and an alining-bar seated in one of the said side ribs and engaging in a groove provided therefor in the corresponding rib of the adjacent rail, and means for rigidly securing said chair to the ties.
2. A device of the class described comprising rails having opposite longitudinal side ribs upon the webs thereof, a rail chair provided with side flanges having inner 25 faces formed complementary to the sides of the rail web, the upper faces of said ribs being inclined and forming V-shaped grooves with the adjacent sides of the rail web and means for rigidly securing said

chair to the ties, the ends of adjacent web ribs having slots in their outer faces, a strip 30 secured in one of said grooves and adapted for slidably seating within the end groove of the adjacent rail web rib.

3. A device of the class described comprising rail ends adapted to abut each other, oppositely positioned longitudinal ribs upon the webs of said rails and having upper inwardly inclined faces, the outer faces of said ribs upon one side of the rails having alining grooves therein, a strip fitting within 35 said grooves, a securing screw through one end of said strip and engaging the adjacent rib, a rail chair having spaced side flanges provided with inner longitudinal 40 grooves complementary formed with respect to said ribs and said chair adapted for 45 slidably mounting upon said rails and means for permanently retaining said chair in position upon the ties.

In testimony whereof I affix my signature 50 in presence of two witnesses.

JOSEPH KUKLA.
